US00D916815S

(12) **United States Design Patent** (10) **Patent No.:** **US D916,815 S**
Sanz et al. (45) **Date of Patent:** **** Apr. 20, 2021**

(54) **DISPLAY SCREEN WITH GRAPHICAL USER INTERFACE FOR PRESENTING USER ACTIVITY TIMELINE IN A COLLOQUIAL STYLE**

(71) Applicant: **GOOGLE LLC**, Mountain View, CA (US)

(72) Inventors: **Gerard Sanz**, Zurich (CH); **Markus Cedric Huebscher**, Adliswil (CH); **Jana Mcsorley**, Zurich (CH); **John Maguire**, Zurich (CH); **Dino Wernli**, Zurich (CH); **Selen Basol**, Zurich (CH); **Johannes Gerardus Maria Vroonhof**, Birmensdorf (CH); **Dorington George Little**, San Francisco, CA (US)

(73) Assignee: **GOOGLE LLC**, Mountain View, CA (US)

(**) Term: **15 Years**

(21) Appl. No.: **29/695,657**

(22) Filed: **Jun. 20, 2019**

CLAIM

The ornamental design for a display screen with a graphical user interface for presenting user activity timeline in a colloquial style, as shown and described.

DESCRIPTION

The FIGURE is a front view of a display screen with a graphical user interface for presenting user activity timeline in a colloquial style, showing the new design.

The outermost broken line rectangle showing the display screen, and all other broken lines showing portions of the graphical user interface, illustrate portions of the article and form no part of the claimed design.
